No. 692,897.

Patented Feb. 11, 1902.

J. G. NOLEN.
TELEPHONE RECEIVER.
(Application filed Apr. 29, 1901.)

(No. Model.)

UNITED STATES PATENT OFFICE.

JAMES G. NOLEN, OF CHICAGO, ILLINOIS.

TELEPHONE-RECEIVER.

SPECIFICATION forming part of Letters Patent No. 692,897, dated February 11, 1902.

Application filed April 29, 1901. Serial No. 57,858. (No model.)

To all whom it may concern:

Be it known that I, JAMES G. NOLEN, a citizen of the United States, and a resident of Chicago, in the county of Cook and State of Illinois, have invented certain new and useful improvements in Telephone-receivers; and I hereby declare that the following is a full, clear, and exact description thereof, reference being had to the accompanying drawings, which form part of this specification.

My invention relates to improvements in telephone-receivers.

One object of my invention is to provide a telephone-receiver in which the magnetic and electrical system may be bodily removed from the protecting-case without disturbing any electrical connections.

Another object of my invention is to provide a means whereby the magnetic system may be adjusted with reference to the diaphragm so that the expansion and contraction of the case will not disturb the adjustment.

Another object of my invention is to provide a number of perforations through the cap-piece which covers the diaphragm, so that the sound may issue therefrom through a number of apertures instead of a central aperture, as is common with instruments of this character.

In the drawings, Figure 1 is a vertical section of my telephone-receiver. Fig. 2 is the inner pole of the magnet carrying the induction-coil and a means by which the said magnet is connected to the surrounding cylindrical magnet, which is a part of the magnetic system. Fig. 3 is a top view of the cap or ear piece of the telephone-case. Fig. 4 is a section through line 4-4 of Fig. 1.

In all of the views the same letters of reference indicate similar parts.

A is the insulating containing-case. a is an annular bead or enlargement around the lower end thereof.

a' is the threaded upper portion, to which the interiorly-threaded cap is attached.

a² is a thread cut into the upper interior portion of the telephone-case A for the purpose of attaching the magnetic system thereto.

a³ is a hard-rubber or other insulating disk

which forms a cap to cover the opening in the lower end of the telephone-case.

a⁴ and a⁵ are screws that are adapted to pass through the cap and to secure it to the magnetic system.

B is a concave cap that is adapted to be screwed over the upper end of the telephone-case for holding the diaphragm in position thereon. b represents a number of perforations through the said cap, which communicate with the space therein over the diaphragm.

C is a magnetized steel tube which forms a part of the magnetic system. c is the rounded polar end of the same.

C' is a magnetized steel rod which forms a part of the magnetic system. c' is the polar end of the said rod, surrounded by the electric coil c². c³ c³ are the terminal binding-posts, which are connected with the said coil and which are attached to the insulating cap-piece a³.

c⁴ is a ring which is fixed tightly around the lower end of the cylindrical magnet C.

c⁵ is an iron cap or yoke for joining the two magnets, in the center of which the magnetized rod C' is secured in the perforation c⁶.

c⁷ is an exteriorly-threaded thimble which is adapted to fit tightly over the upper end of the magnetic cylinder C and which is adapted to be screwed into the threaded interior of the telephone-case A at a². A check-nut c⁸, having spanner-holes in its upper surface, is adapted to be screwed over the exterior-threaded thimble c⁷ for the purpose of securing the magnetic system permanently in position with reference to the diaphragm when it is tightened on the upper portion of the case A after suitable adjustment has been made.

The magnetic circuit between the interior magnetized rod and the surrounding magnetized cylinder is completed through the shoddered iron washer c⁵, which is held in contact with the lower end of the magnetized tube C by means of the screws a⁴ and a⁵, which pass through the cap a³ and the cap or washer c⁵ and into the ring c⁴. By this construction the cap c⁵ is held in contact with the exterior ring, and the insulating-cap a³ is held in position.

thereon, whereby the magnetic and electrical portion of my device becomes as a single unit, which may be bodily removed from the case without disturbing the magnetic or electrical connections or conditions.

I have found from experiment that rounding the upper polar surface of the magnetic cylinder, as shown at *c*, is of great importance and contributes materially to the effective 10 operation of the instrument.

By perforating the cap *B* with small holes *b* instead of using one large hole in the center thereof, as is the usual custom, it becomes a matter of indifference as to the exact position 15 of the telephone-cap with reference to the ear of the operator when using my receiver, as it is hardly possible to hold the cap of the receiver to the ear without the interior of the ear covering one or more perforations in the 20 said cap. Another advantage of perforating the cap of the receiver is to prevent foreign substances from entering the cap or the space between the upper portion of the diaphragm and the said cap. It also prevents meddlesome 25 persons or users of the instrument from disturbing the adjustment by pressing on the diaphragm through the central larger aperture, the perforations in my instrument being so small as to render it impossible for them 30 to materially injure the diaphragm from the exterior of the instrument.

It is sometimes an advantage to be able to remove the entire electrical portion of the instrument from the case without disturbing 35 the connections or their relations and to be able to insert another duplicate or inter-

changeable portion in lieu of the injured or disarranged one that has been removed. The magnet may be secured in the case after it has been properly adjusted for position by 40 tightening the screws *a*⁴ and *a*⁵ to increase the friction upon the threads of the parts *a*² and *c*⁶ and to retain the case and magnet in a fixed relation, in which event the check-nut *c*⁸ may be dispensed with.

It is evident that the cap having the multiplicity of perforations instead of one central perforation, as is usual with telephone receivers and transmitters, may be used with a telephone-transmitter with beneficial results 50 without departing from the gist of my invention.

Having described my invention, what I claim as new and useful, and desire to secure by Letters Patent of the United States, is— 55

In a telephone-receiver the combination of a diaphragm, a cylindrical magnet having its polar end rounded, a magnetized rod within said cylindrical magnet, a coil near the polar ends of said magnet, a case covering said 60 magnets, screw-threads in said case, screw-threads on said magnet, and a check-nut on said magnet for holding said magnet and said case in a fixed relation, substantially as set forth.

In testimony that I claim the foregoing as my own I affix my signature in presence of two witnesses.

JAMES G. NOLEN.

In presence of—
C. INEZ WILCOX,
M. F. ALLEN.
